UNITED STATES PATENT OFFICE.

HANS CHRISTIAN OHLSEN, OF COVINGTON, KENTUCKY, ASSIGNOR OF ONE-HALF TO AUGUST OHLSEN, OF CINCINNATI, OHIO.

VEHICLE-COUPING.

SPECIFICATION forming part of Letters Patent No. 338,546, dated March 23, 1886.

Application filed October 12, 1885. Serial No. 179,683. (No model.)

To all whom it may concern:

Be it known that I, HANS CHRISTIAN OHLSEN, of Covington, Kenton county, Kentucky, have invented a new and useful Improvement 5 in Vehicle-Couplings, of which the following is a specification.

My invention is intended for application to those vehicle-couplings—such as thill-couplings or side-bar spring-couplings—in which 10 one part is connected to a clip on another part by means of a hinge-joint.

My invention relates to improvements in those devices which prevent the parts of the said hinge-joint from rattling against one another. This result I accomplish by the customary expedient of an india-rubber spring or cushion which presses the parts of the hinge-joint into firm and uninterrupted contact.

My invention consists, primarily, of means 20 whereby the said india-rubber spring or cushion may be made to exert the required pressure for efficient action, both when the coupling is put together and when the parts of the same have become worn away by use.

25 In the accompanying drawings, Figure 1 is a vertical section, and Fig. 2 a top view, of a thill-coupling embodying my invention. Fig. 3 is a transverse vertical section of the same on the line 3 3 in Fig. 1. Figs. 4 and 5 are respectively a vertical section and a side view of a side-bar spring-coupling embodying my invention.

I shall first describe my invention as applied to a thill-coupling.

35 A may represent the forward axle, and B the rear end of one of the thills of a vehicle. To the said axle A is attached a clip, C, to which the said thill is connected by means of a hinge-joint, D, the pintle of which is constituted by 40 a bolt, E, which passes through the clip-eyes c and through the thill-eye b, which is inclosed between said clip-eyes. To the rear of the hinge-joint D and inclosed between the clip-eyes is an india-rubber spring or cushion, 45 F, which is contained in a box, G. This box is open in front, and its upper and lower sides, g, inclose the rubber spring or cushion F, and project over the edges of the clip-eyes c, so as to enable said box to be supported by and 50 guided on said clip-eyes. Between the india-rubber cushion F and the hinge-joint D is pref-

erably inserted a brass gib, H, which transmits the pressure of the india-rubber spring to the back of the thill-eye, while preventing the said india-rubber spring from being worn away by actual contact with said thill-eye. 55

A screw, I, is tapped into the clip C, and its head i presses forward against the back of the box G, and is preferably provided with ratchets i' or hole i'', to enable it to be turned 60 by a wrench or pin. The screw I thus constitutes a set screw, by which the box G and its contained india-rubber cushion F may be pushed forward so to bring sufficient pressure against the back of the thill-eye to prevent 65 the parts of the hinge-joint D from rattling against one another. The sides g of the box, together with the inner sides of the clip-eyes c, prevent any vertical or lateral extension of the india-rubber cushion F as it is pushed forward. 70

In putting the coupling together the box G and its contained india-rubber cushion F are put back out of the way until the thill is secured to the clip-eyes. The gib H is then inserted 75 and made to press against the thill-eye b with the required force for efficient action by screwing out the set-screw I.

Whenever, by wearing away of the india-rubber cushion F and the parts of the hinge-joint D, the said india-rubber cushion has been rendered ineffective for its purpose, it may readily be brought into efficient action again by further screwing forward of the set-screw I. 85

An additional advantage of this device consists in doing away with the troublesome operation of holding the india-rubber cushion under considerable pressure out of the way until the thill has been secured to the clip. 90

A similar description to the above applies to my invention as embodied in a side-bar spring-coupling, except as to those differences which arise from the different relative positions of the parts to be coupled. The same 95 letters, therefore, which are used above to refer to parts in Figs. 1, 2, and 3 refer also to similar parts in Figs. 4 and 5, except that in the last-named figures A and B represent, respectively, the side bar and portion of the side-bar spring, while b represents the eye of 100 said spring.

As the clip-eyes *c* of the side bar project downward, the motion of the india-rubber cushion *F* in a side-bar spring-coupling is vertical, and its pressure against the hinge-joint *D* is downward, as shown in Fig. 4. The sides *g* of the box *G* in such a coupling are not above and below, but on each side of the rubber cushion *F*, and it is the top and not the back of said box that receives the pressure from the set-screw.

I claim as new and of my invention—

The combination, with the clip *C*, having screw-threaded orifice, and provided with lugs having eyes *c*, bar *B*, having an eye, *b*, and

a pin, *E*, hinging the bar to the clip, of the gib *H*, bearing on the bar, the cushion *F*, the box *G*, supported between the lugs and having side pieces, *g g*, extending over the lugs, cushion, and gib, and a screw, *I*, adjustable in the orifice and having a recessed head bearing on the box, substantially as set forth.

In testimony of which invention I hereunto set my hand.

HANS CHRISTIAN OHLSEN.
